UNITED STATES PATENT OFFICE

149,707

DESIGN FOR A CRANE CAB

Ernest W. Taylor, Bay City, Mich., assignor to
Industrial Brownhoist Corp., Bay City, Mich.

Application October 4, 1946, Serial No. 133,759

Term of patent 14 years

(Cl. D14—3)

To all whom it may concern:

Be it known that I, Ernest W. Taylor, a citizen of the United States of America and a resident of Bay City, in the county of Bay and State of Michigan, have invented a new, original, and ornamental Design for Crane Cabs, of which the following is a specification, reference being had to the accompanying drawings, forming part thereof.

In the drawings:

Fig. 1 is a side-elevational view of a crane cab, showing my new design.

Fig. 2 is a rear end-elevational view thereof.

Fig. 3 is a front view.

Fig. 4 is a top plan view.

Both sides of the crane cab are exactly the same as shown in Fig. 1 of the drawing.

I claim:

The ornamental design for a crane cab, as shown and described.

ERNEST W. TAYLOR.
